UNITED STATES PATENT OFFICE.

FRANCIS MILLER MACDOWELL, OF FANWOOD, NEW JERSEY, ASSIGNOR TO POWER SPECIALTY COMPANY, OF NEW YORK, N. Y., A CORPORATION OF NEW YORK.

SUPERHEATER BOILER.

Application filed September 17, 1923. Serial No. 363,096.

The general object of the present invention is to provide a novel combination of a superheater with a water tube boiler characterized by the effective manner in which the 5 available space in the boiler is utilized to receive the superheater to provide access for cleaning, inspection, and repairs, and in which the superheater is utilized as a portion of the baffle means employed to give a 10 desirable path of flow over the superheater and boiler heating surface proper, for the heating gases.

The various features of novelty which characterize my invention are pointed out 15 with particularity in the claim annexed to and forming a part of this specification. For a better understanding of the invention however, its advantages and specific 20 objects attained with its use, reference should be had to the accompanying drawings and descriptive matter illustrating a preferred embodiment of the invention.

Of the drawings:

Fig. 1 is an elevation, partly in section, of 25 a portion of a boiler embodying my invention;

Fig. 2 is a section along the line 2—2 of Fig. 1; and

Fig. 3 is a perspective view of a portion 30 of the superheater header and baffle construction.

In the drawings, A represents the housing of a boiler furnace in the upper portion of which is mounted a water tube boiler comprising a mud drum B, front and rear steam and water drums C and D, respectively, and an upper steam drum E. These drums are all horizontal and parallel to one another. The mud drum B which is adjacent to the 40 rear of the furnace housing is connected to the front steam and water drum C by a bank of inclined water tubes F. The drums C and D are connected by a bank of water tubes F'. The tubes F' are approximately 45 horizontal but preferably slope slightly upward from the drum C to the drum D, and are located just below the normal water level. The drums D and B are connected by a bank of water tubes F² which are 50 slightly inclined to the vertical to permit the drum B to be located slightly in front of the rear wall of the boiler housing while the drum D is partially imbedded in that wall. The drum E is located appreciably 55 above the bank of tubes F', between the drums C and D, and somewhat nearer to the drum D than to the drum C. The drum E is connected to the drum C by steam pipes F³ and is connected to the drum D by steam pipes F⁴. As shown the pipes F³ and F⁴ 60 comprise body portions adjacent the drum E sloping downward at a slight angle from the horizontal, and portions adjacent the drums C and D, respectively, which are bowed downwardly.

The superheater is located in the space between the tubes F' and the tubes F³ and drum E. This superheater as shown is of the Foster corrugated tube type, with the tubes G of U shape and connected at their 70 ends to the superheater inlet and outlet headers G' and G², respectively, which extend across the boiler housing. The steam pipe IA leading from the top of the steam drum E is connected to the superheater inlet header G' at one side of the boiler, and the superheater outlet header G² delivers steam to delivery piping (not shown) at either 75 side of the boiler housing. The superheater headers G' and G² are spaced apart by cast iron spacer elements H distributed at intervals along the length of the headers. Cast iron baffle members I, which may be bolted to the spacer elements H, unite with the superheater headers G' and G² and with cast 80 iron saddle members J resting on the header G', and with the bricks K supported on said saddle members to form a heating gas deflecting baffle leading downward from the under side of the drum E to or nearly to 85 the topmost tubes F'. The superheater elements G are also suitably supported and spaced apart by beams L and M and suspension bolts O. A baffle P resting on the top 90 row of tubes F extends upward from the adjacent edge of the tube bank F² toward the drum C. A baffle P' extends vertically upward from the upper edge of the baffle P to the under side of the tube bank F'. A baffle 95 P² immediately beneath the tubes F', extends toward the rear of the boiler from the baffle P'. A baffle R extends along the under side of the tubes F from the front 100 wall of the boiler housing into proximity with the drum B. A baffle Q extends upward along the front side of the bank of tubes F² from the drum B toward the drum D. An extension of the baffle P' extends vertically across the tube bank F' and across 105 the superheater elements G.

With the described construction, the heating gases from the combustion chamber A' of the boiler furnace enter the inter-tube space in the bank of tubes F, between the 5 lower end of the baffle R and the drum B. Thence the heating gases pass longitudinally of the tubes F to the space between the drum C and the baffle P'. Through the last mentioned space and the extension thereof defined by the baffle portion P¹⁰ the heating gases flow upward, after which the heating gases sweep over the top of the baffle P¹⁰ and then flow downward between the last mentioned baffle and the baffle formed by the 10 superheater headers G' and G², and associated parts. The heating gases then flow partly transversely and partly longitudinally of the tubes F' into the bank of tubes F², through the space between the upper end of 15 the baffle Q and the drum D. Thence the heating gases flow downward along the tubes F² to the heating gas outlet A² from the boiler housing, which is immediately to the rear of the drum B. In sweeping around 20 the upper end of the baffle P¹⁰, the heating gases contact with and travel along the steam tubes F³, thereby drying the steam passing from the drum C to the drum E, but the baffle formed in part by the superheater 25 headers, prevent the heating gases from flowing along or in contact with the pipes F⁴ to any appreciable extent as is desirable since these pipes for the main part serve as pressure equalizers rather than as conduits 30 for steam flow and are not adapted to utilize much heat.

In the intended operation of the boiler the water circulation is up from the drum B into the drum C through the tubes F 40 thence across the boiler housing through the tubes F' from the drum C to the drum D, from which the water passes downward to the drum B through the tubes F². The steam generated in the tubes F is liberated 45 in the drum C and passes from thence to the steam drum E through the steam pipes F³. Steam generated in the tubes F' and F², is liberated in the drum D. The steam liberated from the drum D passes to the drum E 50 through the pipes F⁴, but as those skilled in the art will understand, the bulk of the steam generated is liberated in the drum C.

With the described baffle and superheater arrangement, the heating gases sweeping upward over the upper edge of the baffle P' contact with the tubes F³ and impart considerable heat thereto which is desirable for its steam drying and superheating effect, but the baffles prevent any direct or appreciable flow of the heating gases in contact with the tubes F⁴, which is desirable as the limited amount of steam flowing through these pipes makes it neither necessary nor

desirable to supply much heat thereto. The effectiveness of the superheater is enhanced 65 by the flow of the heating gases across the elements G in two transverse passes.

With the described arrangement there is ample space for inspection of, cleaning and 70 repairs to the superheater between the headers G' and G² and the drum D. Access to this space is had through the doorway A³. A doorway A⁴ provides convenient access to the interior of the furnace adjacent the opposite end of the superheater. 75

Having now described my invention, what I claim as new and desire to obtain by Letters Patent, is:

The combination with a water tube boiler comprising a steam and water drum and a water drum adjacent one end of the boiler, a second steam and water drum adjacent the opposite end of the boiler, banks of tubes connecting the water drum to each of the steam and water drums, a third bank of tubes connecting the two steam and water drums, a steam drum parallel to the other drums and located intermediate the ends of the boiler and sufficiently above said third bank of tubes to provide space between 80 said drum and last mentioned tubes for the hereinafter mentioned superheater headers and having a heating gas outlet adjacent said water drum, and tubes connecting said steam drum to each of said steam and water drums, of a superheater located in the space between the steam drum and said third bank of tubes and comprising headers parallel to and beneath the steam drum and tubular superheater elements secured to said headers and extending from the latter toward said 85 opposite end of the boiler in the space between said third bank of tubes and the steam tubes connecting the steam drum to said second steam and water drum, and baffle means including a baffle extending upwardly between the tubes connecting the water drum to the two steam and water drums and across said third bank of tubes, and a baffle formed 90 in part by said headers for causing the heating gases to flow upward toward the last mentioned steam and water drum along the tubes connecting it to the water drum and thence upwardly across an adjacent portion of said third bank of tubes and portions of 95 said third bank of tubes and portions of the superheater elements, and thence downward across the remaining portions of the superheater tubes into said third bank of tubes and thence downward to said outlet through the bank of tubes connecting the 100 first mentioned steam and water drum to the water drum.

Signed at New York city in the county of New York and State of New York this fourteenth day of September A. D. 1923.

FRANCIS MILLER MACDOWELL.
